UNITED STATES PATENT OFFICE.

EDGAR M. GREEN, OF SOMERVILLE, ASSIGNOR OF TWO-THIRDS TO ALFRED H. LORING, OF WEST SCITUATE, AND CHARLES H. GREEN, OF BOSTON, MASSACHUSETTS.

FARE-REGISTER.

SPECIFICATION forming part of Letters Patent No. 389,702, dated September 18, 1888.

Application filed September 27, 1887. Serial No. 250,873. (No model.)

To all whom it may concern:

Be it known that I, EDGAR M. GREEN, of Somerville, in the county of Middlesex and State of Massachusetts, have invented certain new and useful Improvements in Fare Registering and Announcing Devices, of which the following, taken in connection with the accompanying drawings, is a specification.

The object of my invention is to produce a simple and durable apparatus that will accurately register each fare deposited and announce by the ringing of a bell the fact. I attain this object by the mechanism shown in the accompanying drawings, in which—

15 Figure 1 is a side elevation of the works and a vertical section of the case, the instrument being shown in the position it is held by the user, the push-knob being to the right. Fig. 2 is a side elevation of the works as they appear 20 when the push-knob is pressed in—that is, when the swinging shelf, upon which the fare is first placed, is tipped downward, so as to deposit the fare in the cash-receptacle. Fig. 3 is a side elevation of the works and a vertical 25 section of the case, the view being taken so as to show the works from the other side from which they are shown in Fig. 1. Fig. 4 is a plan view, a part of the top of the case being represented as removed for the purpose of showing a portion of the works; and Fig. 5 is an enlarged 30 detail view showing a part of the bell-striking mechanism.

In the drawings, A represents the case that incloses the works, the lower part, R, Figs. 1 35 and 2, serving as a receptacle for depositing the fares.

L is an opening made in the top of the case for receiving the fare, and from which it falls directly upon the swinging shelf C.

40 C⁶, Figs. 1, 2, and 3, is a small piece of glass inserted for the purpose of exposing the fare to view when resting on the swinging shelf C. The swinging shelf C is pivoted on a rod, C⁵, and has a perpendicular wall or back, C', and 45 a curved upper part, C². The part C² serves to close the opening at the lower part of L when the shelf C is tipped, as shown in Fig. 2, so that no fare can reach the shelf C until it has been brought back to its normal position.

The mechanism for operating the swinging shelf C consists of a push-rod and knob, D D', the end of the push-rod being attached by a pin, C⁴, to an ear, C³, formed on the back C' of the swinging shelf C. The push-rod and knob D D' are held back, as shown in Figs. 1 and 3, 50 by a spring, D², one end of which is held by the hook D³, Fig. 3, and the other end is attached to the pin C⁴ at the end of the push-rod D', the strain of the spring D² acting to hold the push-rod D' out and acting through it to 55 hold the swinging shelf C up in its normal position.

I will now describe the bell-striking mechanism. Most of this mechanism is shown in Fig. 1 in elevation. A part of it is shown more 65 clearly in perspective in Fig. 5. On the upper face of the push-rod D', I have a shoulder, B, which, as the push-rod D' is pressed forward, comes in contact with the lower end of the swinging lever B', and as this lever B' is pivoted at B² to the fixed arm A¹ its upper end, b, will swing back against the strain of the flat curved spring B⁴, Figs. 1 and 5. From the upper end, b, of the lever B' a flattened wire, B³, extends. The flat side of the wire B³ is inclined, 70 as shown, and as the end b of the lever B' moves backward it will slide under the projecting upper part of the arm B¹⁵, attached to the handle of the bell-hammer B¹³, and thus raise the bell-hammer up and there hold it until the push rod has tipped the shelf C and has 75 nearly returned to its place. After the lever B' has been turned back so as to hold up the bell-hammer, it is held in place by a tilting piece, B⁶. This tilting piece B⁶ turns on a pivot, 80 B⁷, Fig. 5, and is pushed forward by a spring, B⁸, so that the stud B⁹, Figs. 2 and 5, will come just in front of the upper end, b, of the lever B', as shown in Fig. 2, and hold the said lever back. To remove the stud B⁹ from the front 85 of the lever b B', I have a stud, B¹⁰, (see Figs. 1 and 5,) on the push-rod D', which, as the rod springs back, comes in contact with the lower end of the tilting piece B⁶, and, lifting it, removes the stud B⁹ from the front of the lever 90 b B' and allows it to fly back, and thus allows the hammer B¹³ to strike the bell B¹².

I will now describe the registering mechan-

ism, which is more clearly shown in Figs. 2 and 3.

Upon the push-rod D', I have a stud, d, projecting from the under side. As this stud advances with the push-rod, it will allow the upper end, E', of the lever E' E² to advance under the pressure of the spring E³. This advance of the upper end, E', will cause the lower end, E², of the lever E' E² to recede (as the lever can swing on the pivot E) and cause the pawl E⁴ to fall back behind one of the notches of the ratchet-wheel E⁵ into the position shown in Fig. 2. Now, as the stud d on the push-rod D' returns it will push the upper end, E', of the lever E' E² back, (overcoming the weak spring E³), and thus sending the pawl E⁴ forward and advancing the ratchet-wheel E⁵ one tooth. The ratchet-wheel E⁵ being attached to the shaft E¹⁰, to which the registering-disk E⁶ is attached, it in its movement will advance the disk one unit. A pinion (indicated by dotted lines) is also attached to the shaft E¹⁰. (See Fig. 2.) This pinion has a tenth of the number of teeth that are on the gear-wheel E⁸, to which is attached by a shaft the registering-disk E⁹, the disk E⁹ serving to record the "tens." Other disks may be connected in the usual manner, so as to register any reasonable number.

H is a spring check-door which is pivoted 30 on the wire H' and held in place by a light spring, H². This check-door H is intended to prevent the passage of money from the receptacle R back into the other part of the box. The receptacle R is arranged so that any authorized person may open it and remove the contents.

I claim—

1. The combination of the push-rod D', having a shoulder, B, the lever b B', projecting 40 beveled arm B³, the tilting piece B⁶, stud B⁸, and stud B¹⁰ on the push-rod D', with the bell-hammer B¹², having a lifting-arm, B¹⁵, and the bell B¹⁶, all operating together substantially as described, and for the purpose set forth. 45

2. In a fare registering and announcing device, the combination of the opening or chute L, the shelf C, having a closing-arm, C², the push-rod D, and the receptacle R, with the door H, adapted to be opened by the weight 50 of the coin and to close automatically, all substantially as described, and for the purpose set forth.

EDGAR M. GREEN.
